DESIGN FOR A DRESS

Margaret Pennypacker, New York, N. Y.

Application November 28, 1941, Serial No. 104,361

Term of patent 3½ years

To all whom it may concern:

Be it known that I, Margaret Pennypacker, a citizen of the United States, residing in New York, in the county and State of New York, have invented a new, original, and ornamental Design for a Dress, of which the following is a specification, reference being had to the accompanying drawing, forming part thereof.

Fig. 1 is a front view, and Fig. 2 is a back view of a dress showing my new design.

I claim:

The ornamental design for a dress, as shown.

MARGARET PENNYPACKER.
